UNITED STATES PATENT OFFICE.

HERBERT LOUTH, OF PITTSBURGH, PENNSYLVANIA, ASSIGNOR TO WESTINGHOUSE ELECTRIC & MANUFACTURING COMPANY, A CORPORATION OF PENNSYLVANIA.

IRONING MACHINE.

Application filed November 6, 1920. Serial No. 422,1.

My invention relates to ironing machines and particularly to ironing machines that are power-operated.

My invention has for its object to provide 5 a machine of the character described above, the operative portions of which are supported at a single end.

A second object of my invention is to provide a convenient and efficient means for 10 controlling the operative position of certain of the working parts.

Another object of my invention is to arrange an ironing machine in such manner that it may be employed for purposes other 15 than its normal function when it is not being operated.

A further object of my invention is to provide a simple arrangement whereby selected portions of the ironing shoe may be 20 heated.

An ironing machine constructed in accordance with my invention comprises a cylindrical roll or mandrel that is suspended at a single end. The shoe which coacts with 25 the mandrel is so arranged that it may be heated either wholly or in part, as desired. The shoe, which is movable into and out of operative relation to the mandrel, is controlled by an automatic latching mechanism 30 which operates to effect the raising and the lowering of the shoe upon successive actuations of a controlling pedal.

My invention will be described in connection with the accompanying drawings, in 35 which Figure 1 is a side view, in elevation, of an ironing machine embodying my invention. Fig. 2 is an end view, in elevation, of the machine of Fig. 1. Fig. 3 is a view, partially in elevation and partially in section, of a portion of the ironing machine. Fig. 4 is a top plan view of the machine in 40 Fig. 1. Fig. 5 is a view, in longitudinal vertical section, of a portion of the machine. Fig. 6 is a view, in section, of the shoe and 45 the heating mechanism. Fig. 7 is an end view of a lever member of the automatic latching mechanism. Fig. 8 is a side view of the lever member of Fig. 7. Fig. 9 is a side view of a pivotally mounted member 50 for coacting with the member shown in Figs. 7 and 8. Fig. 10 is an edgewise view of the member of Fig. 9.

The ironing machine comprises a vertical frame member 1, an auxiliary frame mem-

ber 2, a roll 3 and a shoe 4. The frame members 1 and 2 are suitably connected by tie rods 5 to form a rigid supporting structure.

The roll 3 is rotatably supported by a horizontal shaft 6 that is rigidly secured to and supported by the frame member 1. The 60 shaft 6 is prevented from moving longitudinally relatively to the frame member 1 by means of a sleeve 7, that is secured to the shaft, and a nut 8. The roll 3 is mounted on the shaft 6 and the sleeve 7 by cylindrical 65 disks 9 and 10, respectively. The disk 9 is retained in position by means of a shoulder on the shaft 6 and a nut 11.

The disk 10 is provided with a worm wheel 13 that is operatively connected to 70 an electric motor 14 by means of a belt 15, bevel gear mechanism 16 and a worm 17. The worm 17 is maintained in engagement with the worm wheel 13 by a notched lever 18. A spring 19 tends to actuate the worm 75 17 about the pivot of a universal joint 20 to effect the disengagement of the worm gear mechanism and thereby disconnect the motor from the roll.

As best shown in Figs. 4 and 5, the shoe 80 4 is provided with heating elements 22 and 23, which are preferably perforated pipes for the employment of gas. Either part of the shoe may be heated by employing the corresponding pipe 22 or 23, as the case 85 may be, or the entire structure may be heated by the simultaneous employment of both pipes.

The position of the shoe 4, which is pivotally mounted on a rod 24, is controlled by 90 links 25, a pedal 26 and a latching mechanism 27. The weight of the shoe 4 is such that it is normally held in its operative position relative to the roll 3 by the force of gravity. When the pedal 26 is depressed, 95 the shoe is actuated upwardly and it will return to its normal position upon release of the pedal 26 in the absence of restraining means.

The details of the latching mechanism are 100 illustrated in Figs. 7, 8, 9 and 10. It comprises a lever member 28 that is pivotally secured at one end to the lower tie rod 5 and that is provided with lugs 29 pivotally secured to one of the links 25. The pedal 105 26 operates between the lugs 29 and, upon the depressing of the pedal, it engages the main body portion of the lever 28.

An arm 31 is pivotally mounted on a projection 30 of the frame 2, as shown best in Fig. 1, and has a finger 32 thereon adapted to cooperate with finger 33 that is integral with the lever 28 to permit the lever 28 to occupy predetermined positions, and to lock the same in at least one position, as will be hereinafter described. The arm 31 has pivotally mounted thereon a wedging block 34 that normally rests upon the shoulder 34a (Fig. 10) so as to limit the downward movement thereof.

The operation of the shoe 4 and the controlling mechanism will now be described, 15 assuming the ironing elements are in operative position, with finger 32 projecting below finger 33. As the pedal 26 is depressed to engage the short lever 28, the pedal 26 engages the triangular block 34 to exert a 20 wedging or cam action upon the part 31, whereby the latter is actuated laterally (toward the frame 2) to the pedal 26 and the projection 32 is moved out of the path of the projection 33.

25 Upon the further depression of the pedal 26, to substantially the limit of its downward movement, the pedal passes below the block 34 permitting the member 31 to swing inwardly to such position that the projection 32 is above the projection 33. The pedal 26 may be released, whereupon it is actuated upwardly by means of a spring 35, the block member 34 being freely movable upwardly in order that the position of the member 31 30 is not disturbed as the pedal 26 returns to its normal position. The shoe 4 is now held in its inoperative position without further attention on the part of the operator.

In case it is desired to operate the machine, it is only necessary for the operator 40 to again depress the pedal 26 to such extent that it again engages the block 34 to shift the member 31 laterally thereby moving the projection 32 out of the path of the projection 33. The arrangement of parts is such that as soon as projection 32 clears projection 33, the lever 28 will move upwardly so that the projection 32 cannot, during this 45 operation of the pedal, return to its position above projection 33. Coincident with the upward movement of the lever 28 the shoe 4 is moved toward its operative position which movement is completed after the release of the pedal 26 by the operator. It 50 will be obvious that movements of the pedal in the same direction operate to alternately obtain the movement of the shoe to and from its operative position.

An additional feature of my invention is 55 the provision of a pivotally-mounted shelf 37 for supporting articles of clothing to be, or being, ironed and which may be swung outwardly to constitute an ironing board or it may be used for a shelf for various purposes when the ironing machine is not in

use. This arrangement also permits circular articles to be ironed.

The advantages of an ironing machine constructed in accordance with my invention will be obvious to those skilled in the art. 70 The provision of a roll that is secured at a single end renders it capable of employment in connection with garments or other articles that must otherwise be ironed manually. The ease and convenience with which 75 the machine may be operated renders this construction extremely desirable. This arrangement is successfully provided in my improved ironing machine by providing a supporting frame member, the side portions 80 of which are sufficiently spaced to constitute a rigid support for the horizontal shaft for supporting the roll.

The provision of means for heating either 85 the whole or a part of the shoe enables the user to economize fuel in case articles of a small size only are to be operated upon by the machine.

The provision of the automatic latching mechanism enables the operator to change 90 the position of the shoe by the simple actuation of the pedal. The position of the shoe is changed regardless of the position it occupies by a simple depression of the pedal. It is only necessary to exercise ordinary care 95 to effect the release of the shoe in order that it may return to its operative position. It is not necessary for the operator to maintain the pedal in the depressed position as is the case in machines of the prior art having 100 similar controlling means.

I claim as my invention:

1. In an ironing machine, the combination with an upright frame member, of a horizontal member secured thereto, a cylinder rotatably mounted on said horizontal member, and means for preventing relative longitudinal movements of said cylinder and said horizontal member, said preventing means comprising a disk secured to said cylinder and having a bearing on said horizontal member, a shoulder on said horizontal member and means for retaining said disk adjacent to said shoulder. 110

2. In an ironing machine, the combination with a rotatable member and a shoe member co-operating therewith, of means for actuating said shoe member alternately to its operative position and to its inoperative position upon similar and successive manipulations of said actuating means, said means comprising a latching mechanism, a lever connected to said shoe, and a second lever for effecting the engagement and the release of the first lever by said mechanism upon successive operations of the second lever. 115 120 125

In testimony whereof, I have hereunto subscribed my name this 30th day of Oct., 1920.

HERBERT LOUTH.
